UNITED STATES PATENT OFFICE

LLOYD M. KEIGHLEY, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed November 10, 1926. Serial No. 147,550.

This invention relates to cooling units for mechanical refrigerators, and more particularly to cooling units which are adapted to be installed in refrigerating cabinets of the household type. However, it is to be understood that the present invention may be adapted for larger refrigerating cabinets of the commercial type.

The present invention includes among its objects the provision of a cooling unit of simple and economical construction, which will quickly congeal or freeze substances which are placed within a freezing compartment provided by the unit, and which will effectively cool the food compartment of the cabinet.

Further objects and advantages of the present invention will be apparent from the following description, reference being had to the accompanying drawings, wherein a preferred form of the present invention is clearly shown.

In the drawings:

Fig. 1 is a front view of a refrigerator cabinet with the doors open in order to show the food compartment and a cooling unit within a cooling compartment;

Fig. 2 is a view on a larger scale than Fig. 1, showing the front view of the cooling unit which is suspended within the cooling compartment of a cabinet, the walls of which are shown in vertical section; and

Fig. 3 is a side elevation of the cooling unit drawn to the same scale as Fig. 2.

Referring to the drawings, 20 designates a refrigerator cabinet which provides an L-shaped food compartment 21 separated from a cooling compartment 22 by a horizontal partition 23 and a vertical partition 24. The partition 24 is provided with a flue 25, admitting relatively warm air from the food compartment 21 to the cooling compartment 22; and the partition 23 is provided with a flue 26, admitting cooled air from the compartment 22 to the compartment 21. The partition 23 supports a baffle 27 which prevents moisture dripping from the cooling unit above from entering the flue 26. The baffle 27 directs such moisture upon the upper surface of the partition 23, and this

moisture is conducted away through a drain pipe 28.

The cooling unit located within the cooling compartment 22, includes a boiler or header 30 attached to the top wall of the cabinet by bracket members 31 and 32. Condensed refrigerant is conducted to the header 30 from a compressor and condenser (not shown) through a pipe 33 and a fitting 34. Refrigerant is admitted from the fitting 34, as needed, by a float-controlled valve (not shown), of suitable construction, located within the header 30. Expanded refrigerant is conducted back to the compressor through a fitting 35 and a pipe 36. The refrigerating compressor and condenser with which the pipes 33 and 36 are connected, may be located outside of the cabinet, if desired, or may be placed within a machine compartment located below the food compartment 21, said compartment having a removable front wall 37 provided with louvers 38.

A plurality of looped conduits 40 and 41 of metal of good thermal conductivity are connected with the header 30, and are arranged in horizontal rows, the row of loops 40 enclosing the row of loops 41. The loops 40 are so located as to be almost entirely subjected to the air which circulates adjacent the cooling unit. The loops 41 each comprise a plurality of serpentine bends, the bends of the vertical legs of the loops 41 being vertically superposed, and the bends of the yoke portion or bottom portion of the loop being horizontally adjacent. Preferably the serpentine loops are formed in the ducts 41 before the ducts are bent at the corners A, B, C and D to form structures which are adapted to co-operate with the header 30 to provide a quick freezing space 42 below the header.

By virtue of this construction a cooling unit is provided having what may be termed a freezing zone formed by the ducts 41 for quickly freezing or congealing a substance, and, what may be termed a cooling zone formed by ducts 40 which ducts cool the circulating air to the desired temperature, not too cold for general refrigeration within the refrigerator. The freezing zone being nest-

ed within the cooling zone is protected thereby from the warming action of the air passing over the unit.

Usually the loops 41 are first joined to the header and then one or more metal sleeves 43 are inserted in the space 42 and are thermally joined at their side walls to the serpentine bends of the loops 41. Due to the serpentine formation of the bottom or yoke portions of the loops 41, these loops may be spread or contracted to adjust the distance between the corner bends A and B so that the vertical branches of the loops 41 can be made to fit snugly the side walls of the sleeves 43. The bottom walls of the bottom sleeve 43 may be thermally joined to the yoke portion of the loops 41 so as to increase the area of thermal contact between this sleeve and the loops. In this way the bottom sleeve may be subjected to lower temperature conditions than the other sleeves. The sleeves 43 receive metal trays 44 containing matter to be frozen.

Due to this serpentine configuration, the loops 41 provide not only relatively great area of thermal contact with the sleeves 43, but also provide wall portions of substantial area which protect the trays from warmer circulating air. Frost which will quickly accumulate upon the loops 41, provide further insulation or isolation of the freezing space. During the idle period of the refrigerating machine, the loops 40 may be defrosted under conditions of warm temperature surrounding the cabinet, but some frost will remain upon the coils 41 even under such conditions owing to the relatively great area of the coils 41 which is exposed to frosting. Thus the present invention provides for very rapid freezing of water or other substances, while providing adequately for cooling the air circulating within the cabinet.

While the form of embodiment of the present invention as herein disclosed, constitutes a preferred form, it is to be understood that other forms might be adopted, all coming within the scope of the claims which follow.

What is claimed is as follows:

1. A cooling unit for mechanical refrigerators comprising, a header, looped conduits depending from the header, a part of said conduits having tortuous branches and cooperating with the header to enclose a freezing space, the other conduits being spaced more remotely from the freezing space.

2. A cooling unit according to claim 1 in which the loops spaced more remotely from the freezing zone, have substantially straight branches.

3. A cooling unit for mechanical refrigerators comprising, a header, looped conduits depending from said header, certain of said conduits having both branches provided with superposed, serpentine bends, co-operating with the header to enclose a freezing space,

the other conduits being spaced more remotely from said freezing space.

4. A cooling unit for mechanical refrigerators adapted to be placed in the path of the medium to be cooled thereby, said cooling unit comprising a set of duct loops providing a freezing zone, another set of duct loops providing a cooling zone, the material of the second set lying outwardly of the freezing zone in the path of the medium and so constructed and arranged as to provide a shield of heat exchange material for shielding the freezing zone from the action of the circulating medium, the loops of one of said sets having upright branches having tortuous portions disposed longitudinally of the freezing zone.

5. A cooling unit for mechanical refrigerators adapted to be placed in the path of the medium to be cooled thereby, said cooling unit comprising duct loops having upright branches providing a freezing zone said branches having tortuous portions disposed longitudinally of the freezing zone, another duct loop providing a cooling zone, the material of the second duct loop lying outwardly of the freezing zone in the path of the medium and so constructed and arranged as to provide a shield of heat exchange material for shielding the freezing zone from the action of the circulating medium.

6. A cooling unit for mechanical refrigerators adapted to be placed in the path of the medium to be cooled thereby, said cooling unit comprising a plurality of duct loops certain of said loops having opposed upright tortuous branch portions cooperating to provide a freezing zone therebetween and certain other of said duct loops providing a cooling zone, the material of the second-mentioned portion lying outwardly of the freezing zone in the path of the medium and so constructed and arranged as to provide a shield of heat exchange material for shielding the freezing zone from the action of the circulating medium.

7. A cooling unit for mechanical refrigerators adapted to be placed in the path of the medium to be cooled thereby, said cooling unit comprising duct means extending vertically to provide a freezing zone said branches having tortuous portions disposed longitudinally of the freezing zone, said cooling unit including heat exchange material formed to provide a cooling zone, said heat exchange material lying outwardly of at least three sides of the freezing zone in the path of the circulating medium and so constructed and arranged as to provide a shield of heat exchange material for shielding the freezing zone from the action of the circulating medium.

8. A cooling unit for mechanical refrigerators comprising an ice tray support, conduits each including opposed branch portions in

- intimate thermal contact with the opposite sides of the support and a connecting yoke portion, said yoke including a tortuous portion of flexible material for permitting shifting of one branch with respect to the other.
- 5 9. A cooling unit for mechanical refrigerators comprising an ice tray support, conduits each including opposed branch portions in intimate thermal contact with the opposite sides of the support and a connecting yoke portion, said yoke including a tortuous portion of flexible material lying alongside said support.
- 10 10. A cooling unit for mechanical refrigerators comprising a header, depending duct loops having the ends thereof connected with the header and having the branches thereof spaced from one another to provide a freezing zone therebetween and below the header,
- 15 20 certain of said branches having tortuous portions lying longitudinally of the freezing zone.
- 25 11. A cooling unit for mechanical refrigerators comprising an ice tray support, a header, depending duct loops having the ends thereof connected with the header and having the branches thereof spaced from one another to provide a freezing zone therebetween and below the header, certain of said branches
- 30 30 having tortuous portions lying longitudinally of the freezing zone and in intimate thermal contact with said support.

- 35 12. A cooling unit for mechanical refrigerators comprising a header, depending duct loops having the ends thereof connected with the header, the opposed branches of the loops providing a freezing zone therebetween and below the header, said opposed branches having tortuous portions lying longitudinally of
- 40 the freezing zone.

In testimony whereof I hereto affix my signature.

LLOYD M. KEIGHLEY.
